[57] CLAIM

The ornamental design for a “case for a compact disc,” as shown and described.

DESCRIPTION

FIG. 1 is a perspective view of a case for a compact disc, showing my new design;

FIG. 2 is a front view thereof;

FIG. 3 is a rear view thereof;

FIG. 4 is a left side view thereof;

FIG. 5 is a right side view thereof;

FIG. 6 is a plan view thereof, taken from above; view from below being mirror-like; and,

FIG. 7 is a perspective view thereof, taken in open condition.
